CLAIM

The ornamental design for a front sensor housing, as shown and described.

DESCRIPTION

The present application is related to U.S. Design patent application Ser. No. 29/688,905, entitled Rear Sensor Housing, filed concurrently herewith, the entire disclosure of which is incorporated by reference herein.

FIG. 1 is a front perspective view of a front sensor housing according to a first embodiment of our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of a front sensor housing according to a second embodiment of our design;

FIG. 9 is a front elevation view thereof;

FIG. 10 is a back elevation view thereof;

FIG. 11 is a right side elevation view thereof;

FIG. 12 is a left side elevation view thereof;

FIG. 13 is a top plan view thereof;

FIG. 14 is a bottom plan view thereof; and,

FIG. 15 is a front perspective view of the front sensor housing of the first embodiment positioned on an exemplary vehicle.

The broken lines in the figures illustrate portions of the front sensor housing that form no part of the claimed design. The broken lines shown in FIG. 15 illustrate an exemplary vehicle that forms no part of the claimed design.

The specific placement of the front sensor housing in FIG. 15 on the exemplary vehicle is for illustrative purposes only and does not limit placement of the front sensor housing to a specific location on a vehicle or other object.
